tion of Illinois

Application December 7, 1935, Serial No. 53,311

8 Claims. (Cl. 22—70)

This invention relates to machines for die-casting metals under relatively high pressures. The particular object of the invention is to provide a die-casting machine which shall be capable of automatically and rapidly performing a cycle of operations in proper sequence and in proper time relation, so that the metal shall be cast under the desired pressure and the die opened after sufficient time has elapsed to permit the metal to congeal.

In the accompanying drawings, Figure 1 is a side elevation of a die-casting machine embodying the features of my invention.

Fig. 2 is a plan view of the machine. In Figs. 1 and 2 the die is shown closed.

Fig. 3 is a fragmental side elevation, showing the die open.

Fig. 3^a is a section on line 3—3^a of Fig. 3.

Fig. 4 is a fragmental sectional view, showing the die closed.

Fig. 5 is a section on line 5—5 of Fig. 1.

Fig. 6 is a section on line 6—6 of Fig. 1.

Fig. 7 is a section on line 7—7 of Fig. 4.

Fig. 8 is a section on line 8—8 of Fig. 4.

Fig. 9 is a section on line 9—9 of Fig. 7.

Fig. 10 is a diagrammatic illustration of the machine.

Figs. 11, 12 and 13 are sectional views of certain valves.

Fig. 14 (Sheet 5) is a fragmental plan view of an alternative form of core-pulling and inserting mechanism.

Fig. 15 is a section on line 15—15 of Fig. 14.

The embodiment herein shown of the invention comprises a supporting framework consisting of a base 1, a platen 2, brackets 3 and beams 4 to which the platen 2 is rigidly secured, and two parallel inclined rails 5 supported above the base 1 on the brackets 3 and 6. The framework of the machine further comprises four guide- rods 7 rigidly secured to and extending perpendicularly from the platen 2. The outer ends of the guide rods 7 are supported in a frame 8 having rollers 9 which stand on the rails 5. As shown in Fig. 1, the outer ends of the guide rods 7 are screw-threaded and extend through openings in the frame 8, being secured to said frame by means of nuts 10. The screw-thread connection between the guide rods 7 and the frame 8 permits the frame to be secured at the proper distance from the platen 2 in accordance with the dimensions of the dies.

The die comprises a stationary section 11 which is detachably secured to the platen 2, and a movable section 12 which is detachably secured to a

carriage 13 (Figs. 1 and 6). Said carriage is slidably mounted on the guide rods 7 and has wheels 14 that run upon the rails 5. It will, of course, be understood that the shape and dimensions of the die-sections 11 and 12 will vary in accordance with the work in hand.

The die-section 11 may be secured to the platen 2 in any desired manner, as by means of clamp members 14^a (Figs. 4 and 7) and may be accurately located on the platen by means of dowel pins 14^b.

The means for moving the die-section 12 into and out of contact with the die-section 11 and for locking the die-sections in tight contact with each other comprises four pairs of toggle links 15, each pair of links being pivoted at one end to the carriage 13 and at its opposite end to the frame 8. When the toggles are in aligned position, as shown in Figs. 1 and 4, two of the toggles extend close to the plane of the two upper guide rods 7 and the other two toggles extend close to the plane of the two lower guide rods 7. The upper toggles are connected at their mid-points to the mid-points of the lower toggles by means of links 16. It will be seen that the four toggles 15 and 20 the links 16 constitute a parallel-motion connection by means of which the carriage 13 may be moved toward and away from the platen 2. The means for flexing and straightening the toggles 15 to reciprocate the carriage 13 and to hold the die-section 12 tightly pressed against the die-section 11 comprises a cylinder 17 having trunnions 17^a (Fig. 3^a) that are carried in bearings on brackets 18 which are rigidly secured to the frame 8. The cylinder 17 is located at one side of the path of movement of the die-section 12. In said cylinder is a piston 19 which is secured to a plunger 20, said plunger being attached to a crosshead 20^a which is pivoted to the mid-points of two pairs of toggle links 21. The lower ends of the pair of 40 toggle links 21 are pivoted to the mid-points of the lower pairs of toggle links 15 (Fig. 5). The upper ends of the two pairs of toggle links 21 are pivoted to the brackets 18 at 21^a which is at one side of the path of movement of the die-section 12, thus making possible the use of relatively long toggle links 21. The locked position of the toggles 15 and 21 is determined by contact of the piston 19 with a stop portion 21^b (Figs. 3^a and 4). By means of the toggles 15 and 21 I am enabled to hold the movable die-section pressed against the stationary die-section with great force so as to withstand the pressure under which the molten metal is forced into the die, thus obtaining pre- 55

cision in the casting of the metal, and preventing the escape of metal between the die-sections.

Means has been provided for automatically inserting cores into the impression or impressions ⁵ *a* (Figs. 6 and 9) formed between the dies and for automatically withdrawing the cores. In the present instance, means has been provided for thus operating two cores, but it will be understood that in practice the number of cores will depend upon the number and character of the casting or castings to be formed. The cores are indicated in Figs. 3 and 6 by the number 22. They are mounted for rectilinear movement perpendicularly to the direction of movement of the die-section 12 in guides 22^a fastened to said die-section, and are attached to heads 22^x. Each head 22^x has a guide pin 22^z that fits slidably in an opening in the die-section 12. The heads 22^x have a screw-thread adjustable connection to 20 yokes 22^b. These yokes are connected by means of links 23 to levers 24. Said levers are pivoted on the pivot bolts 25 to brackets 26 rigidly secured to the carriage 13. To prevent the brackets 26 from springing under the pressures exerted in 25 operation, they are rigidly connected to the die-section 12 by means of rods 26^a. As shown in Fig. 3, several openings are formed in each bracket 26 and lever 24 to receive the pivot bolt 25 in order that the extent of movement of the 30 core 22 may be adjusted by placing the pivot bolt 25 in selected openings in the lever and the bracket. The rear arm of the upper lever 24 is secured to a yoke 27. The lever 24 may be secured to the yoke 27 at various points in accordance with the position of the core relative to the die-sections, the bolts 28 (Fig. 6) being insertable into selected openings 29 in the yoke 27. The arms of the yoke 27 are connected to the frame 8 by means of links 30 and brackets 30^a (Fig. 5), said brackets being attachable at various points as indicated by the series of screw holes 30^b (Fig. 3). The link 30 may be connected with the yoke 27 at either of two points, as shown in Fig. 3.

45 The rear arm of the lower lever 24 is connected to the frame 8 by means of a link 30^c. It will be seen that as the carriage 13 is moved, the cores 22 will be moved into or out of the impressions *a*, depending upon the direction of movement of the carriage.

If cores are to be inserted and withdrawn at right angles from the position shown in the drawings, the brackets 26 may be secured to the vertical sides of the carriage 13, at selected points, as indicated by the screw holes 30^d (Fig. 3). In such a re-arrangement, the links 30 are attached to appropriate sides of the frame 8.

Figs. 14 and 15 illustrate an arrangement for horizontally inserting and withdrawing two cores. 60 Two brackets 135 are adapted to be secured to a vertical side of the carriage 13 by means of screws 136, a plurality of holes 137 being provided in the carriage to permit of locating the brackets at desired points. To facilitate the handling of the brackets 135 when the latter are being located on and secured to the carriage, I provide supporting means comprising a bracket 138 fixed to the carriage and rotatably supporting a screw 139 that extends freely through an aperture in the upper bracket 135 and engages a threaded hole in the lower bracket. Nuts 140 on the screw 139 confine the upper bracket 135 in adjusted position. A crank 139^a affords means for rotating the screw 139 when the brackets 135 75 are to be adjusted.

Each bracket pivotally supports a lever 141, a plurality of pivot holes being formed in the bracket and the lever to afford a range of adjustment. One arm of each lever is connected to a core by means of a link 142. The opposite arm of the lever is connected to the frame 8 through a link 143. It will be evident that as the carriage 13 and die-section 12 move forward and back the cores will be inserted and withdrawn. To prevent springing of the brackets 135 as the cores are pulled, each bracket is connected to the die-section 12 by means of a tie-rod 144.

The means for supplying molten metal under pressure to the die comprises a pot 31 (Fig. 4) and a furnace 32, each of which may be of any preferred character. The pot 31 is located close to the platen 2. A pump cylinder or well 33 is stationarily supported in the pot 31, one end of the cylinder communicating with the interior of the pot by means of an inlet port 34 and the opposite end of the cylinder communicating with a gooseneck 35 by means of a channel 36. A plunger 37 in the pump cylinder 33 is connected to a piston 38 in a cylinder 39 mounted on the frame 4. Preferably the plunger 37 is connected to the rod of the piston 38 by means of a member 39^a so that the plunger may be easily detached and removed when cleaning or replacement is required. Forces tending to separate the cylinders 33 and 39 are counteracted by the tie-rods 39^b (Fig. 8) and turnbuckles 39^c.

It will be seen that by operating the piston and cylinder 38—39, molten metal may be forced from the pump cylinder 33 and through the gooseneck 35 to an inlet member 40 which extends between the end of the gooseneck 35 and the gate 41 of the die-section 11.

A spreader pin 42 secured to the die-section 12 extends into the gate 41 to aid in directing the stream of molten metal to the several impressions 40 of the die.

The means for ejecting or freeing a casting from the movable die-section 12 is herein shown as consisting of a suitable number of pins 43 fixed to a head 44. The pins 43 extend slidably through openings in the movable die-section 12, said openings extending to the impressions *a* of the die. The head 44 is secured to the piston rod 45 of a cylinder 46, said cylinder being mounted upon the carriage 13 parallel with the guide rods 7. A rod 47 is secured to the head 44 and to a crosshead 48 on the piston rod 45, the rod 47 extending through a guide opening 49 in the carriage 13. 49^a is a guide rod fixed to the carriage 13 and extending through an opening in the crosshead 48. Two pins 50 fixed to the head 44 extend slidably through openings in the movable die-section 12 into contact with the stationary die-section 11 when the die is closed. In the closing movement of the die-sections, the pins 50 engage the die-section 11 and thus insure that the ejector pins 43 shall be retracted from the impressions *a*.

It will be apparent from the foregoing that power to move the die-section 12 into and out of operative position and to lock it in operative position, and to pull and insert the cores 22 is furnished by the cylinder 17; that power for forcing molten metal into the die is obtained from the cylinder 39, and that power to eject the castings 70 from the die is supplied by the cylinder 46. The means herein shown for supplying pressure fluid to these cylinders in proper timed relation and under the control of the operator will now be described.

A power unit 60 of well-known construction is connected to an oil reservoir 61 by means of a supply pipe 62. In the present embodiment of the invention I have shown a power unit manufactured by Vickers Incorporated, of Detroit, Michigan, comprising two positive displacement pumps 60^a and 60^b of the sliding vane type, but it will be understood that my invention is not limited to the use of such a power unit. The pumps 60^a and 60^b are arranged to be continuously driven at the same speed by means of an electric motor M or other source of power. A valve unit 60^c of known construction is connected between the pumps 60^a and 60^b and a pressure supply pipe 66 and a return pipe 67. A by-pass line 63 extends between the valve unit 60^c and the tank 61. In said line is a by-pass valve 64 which may be opened and closed by a handle 65.

The flow of oil to and from the die-and-core-operating cylinder 17 is controlled by means of a valve A. The cylinder 39 that forces molten metal into the die is controlled by means of a valve B, while the cylinder 46 that operates the ejector is controlled by means of a valve C.

Oil under pressure is supplied to the valves A, B and C by means of the branched pipe 66. Oil which is exhausted from the cylinders through said valves is returned from the valves to the reservoir 61 through the branched pipe 67.

Referring first to the connections between the die and-core-operating cylinder 17 and its controlling valve A: The slideable valve member of said valve is arranged to connect the supply pipe 66 alternately to pipes 68 and 69 leading to the opposite ends of said cylinder. Fluid exhausted from the cylinder 17 through the pipes 68 and 69 leaves the valve through the ports 70 and 71, respectively, and thence flows through a passage 72 that communicates with the drain pipe 67.

The opposite ends of the pressure casting cylinder 39 are connected to the valve B by means of pipes 73 and 74. Fluid forced from said cylinder through said pipes leaves the valve B through ports 75 and 76 and flows thence to a passage 77 that connects with the drain pipe 67.

An accumulator tank 78 is connected at its upper end to a source of compressed air so that the tank may be charged with air under a pressure of say, 400 or 500 pounds per square inch. After thus charging the tank with compressed air, the source of supply is shut off by a valve 78^a so as to confine the charge of air in the tank. 78^b, 78^c and 78^d are drain cocks connected to the tank at different heights. The lower end of the accumulator tank 78 is connected to the valve B through a pipe 79. The slideable valve member of the valve B is arranged to connect the pipes 73 and 79 or the pipes 74 and 66, depending upon the position of said valve member. The pipe 66 is connected to the accumulator tank 78 through a pipe 80, a pressure-regulating valve 81 in the pipe 66 serving to supply oil under the desired pressure (say 1,000 pounds per square inch) to the pipe 80. 81^a is a check valve interposed between said pipes to prevent flow of oil from the pipe 80 to the pipe 66. The slideable valve member of the valve C is arranged to connect the pipe 66 alternately with pipes 82 and 83 leading to opposite ends of the ejector cylinder 46. Fluid exhausted from the cylinder 46 flows through ports 84 and 85 to a passage 86 and thence to the drain pipe 67.

The valves A and B are arranged to be operated in succession under fluid pressure. For this purpose one end of the valve A is arranged to be supplied with pressure fluid through a tube 87 that

extends from a valve D. The construction of this valve is best shown in Fig. 11. The other end of the valve A is arranged to be supplied with pressure fluid through a tube 88 also connected to the valve D. A drain tube 89 extends from the valve D to the reservoir 61. A tube 90 connects the valve D to the pressure supply pipe 66.

As shown in Fig. 11, the oscillatory valve member 91 of the valve D has a peripheral groove 92. In the initial or idle position shown in Figs. 10 and 11, the groove 92 connects the tubes 89 and 87 so that pressure fluid is supplied to the valve A to hold said valve in the position shown in Fig. 10. The valve member 91 also has a peripheral groove 93 which, in the position shown in Fig. 11, connects the opposite end of the valve A through the tube 88 to the drain tube 89. When the valve member 91 is moved clockwise to its operated position, the groove 92 connects the tubes 87 and 88, and the groove 93 connects the supply tube 88 with the tube 89, thereby causing the valve A to operate to connect the supply pipe 66 with the pipe 68 and to connect the pipe 69 with the outlet port 71. The piston 19 is thereby driven downwardly to close and lock the die.

The valve member 91 is provided with a hand lever 94 for manually operating the valve D to supply pressure fluid to the cylinder 17. Automatic means is provided for restoring the valve D to its initial position after a suitable interval, said means comprising a cylinder 95 containing a piston 96 having attached thereto a trip projection 97 arranged to engage an arm 98 fixed to the valve member 91. One end of the cylinder 95 is connected through a tube 99 to a valve 100 connected into the pipe 73. The valve 100 is of any conventional construction adapted to open communication between the pipes 73 and 99 when the pressure in the pipe 73 reaches a desired point, as, for example, 1000 pounds per square inch. The opposite end of the cylinder 95 is connected through a tube 101 to a valve 102 which is similar to the valve 100, the valve 102 being connected into the pipe 74. In the tube 101 is a timing valve 102^a to retard the flow of the oil to the cylinder 95, but to allow oil to exhaust freely from the upper end of said cylinder when the trip 97 is reset. Any preferred construction of timing valve may be employed, as, for example, that shown in Fig. 13. As therein shown, the valve member 102^b restricts the flow of oil in one direction, while the ball valve 102^c permits oil to flow freely in the opposite direction.

The valve B, like the valve A, is arranged to be operated by fluid pressure. The opposite ends of the body of the valve B are connected to a valve E by means of tubes 103 and 104. 105 is a tube connecting the valve E to the pressure supply pipe 66. 106 is a drain pipe connecting the valve E to the drain pipe 67. The valve E comprises an oscillatory valve member 107 (Fig. 12) having a peripheral groove 108 which, when the valve is in the position shown in Figs. 10 and 12, connects the pressure supply pipe 105 with the tube 104; and a groove 109 which connects the pipe 103 to the drain pipe 106. When the valve member 107 is in the opposite position the pressure supply tube 105 is connected to the tube 108 through the groove 109, and the pipes 106 and 108 are connected through the groove 108.

The valve E is arranged to be automatically operated by two trips such, for example, as those illustrated in Fig. 10. 110 is a cylinder, one end of which is arranged to be supplied with pressure fluid through a tube 111 extending from 76.

the pipe 69. The other end of the cylinder 110 is supplied with pressure fluid through a tube 112 which is connected to a valve 113. The valve 113 is connected through a tube 114 to a valve 115 which is similar to the valves 100 and 102, the valve 115 being connected into the tube 68. A shut-off valve 116 is connected into the tube 114.

The valve 113 comprises a slidable valve member 116 which is normally held in the closed position shown in Fig. 10 by means of a spring 117. 118 is a drain tube connected to that end of the valve 113 which contains the spring 117. The valve member 116 is arranged to be slid into position to establish communication between the tubes 114 and 112 by means of an arm 119 (Fig. 4) fixed to one of the toggle links 15 in position to engage the stem 120 of the valve member 116 and open communication between the tubes 114 and 112 after the die-sections have been locked in tight contact.

In the cylinder 110 is a sleeve valve 121 which is arranged to control communication between the tube 112 and a drain tube 122 that connects with the tube 106. In the position shown in Fig. 10, such communication is prevented. A piston 123 slidably mounted in the sleeve valve 121 carries a trip projection 124 that is arranged to engage an arm 125 fixed to the valve member 107. 30 A trip 126, similar to the projection 124, is arranged to engage an arm 127 fixed to the valve member 107. The trip 126 is arranged to be operated by a fluid-pressure actuator 126^a similar to the actuator 110, 121, 123, both actuators being connected to the pressure supply tube 111 and to the drain tube 122. Pressure fluid is arranged to be supplied to one end of the actuator for the trip 126 through a tube 128 which is connected to the tube 99, a timing valve 128^a being connected into the tube 128.

Swivel joints are provided in the various pipes to permit of the required movement of the cylinders 17 and 46.

The valve C is arranged to be manually operated to cause ejection of the castings. 130 is a hand lever connected to the valve member of the valve C and normally held by a spring 131 in position to prevent actuation of the ejector.

The operation of the machine may be summarized as follows:

After starting the motor M, the by-pass valve 64 is closed by shifting the handle 65 to the position shown in Fig. 10. The power unit 60 then builds up a pressure of, say, 1000 pounds per square inch on the oil in the pipe 66. Oil flows through the valves 81 and 81^a and the pipe 80 to the accumulator tank 78 until the oil reaches or slightly exceeds the level of the drain cock 78^b, any excess being drained through said cock. 60 The cock is then closed and the motor M stopped. Compressed air is then admitted to the tank 78 until the desired pressure, say, 400 or 500 pounds per square inch, is reached, the valve 78^a being then closed. The motor M is then restarted, 65 whereupon oil is forced into the tank 78 through the valves 81 and 81^a until the pressure in the tank reaches the desired working pressure as determined by the valve 81. The dotted line x indicates the approximate level of the oil in the 70 tank.

With the machine in the position shown in Fig. 3, the operator turns the hand lever 94 (Fig. 10) in the clockwise direction to connect the pressure supply tube 90 with the tube 88, thereby 75 causing the valve member of the valve A to move

to the position opposite to that shown in Fig. 10, thus connecting the pressure supply pipe 66 to the pipe 68, and connecting the pipe 69 to the drain pipe 67. The piston 19 is thereby driven downwardly to close the die-sections and lock them tightly together. As the closing and locking operation is consummated, the valve 113 is operated to establish communication between the tubes 114 and 112, but pressure is not immediately supplied through said tubes to the trip actuator 123, because the valve 115 does not open to supply pressure fluid to the tube 114 until the pressure in the tube 68 and the upper end of the cylinder 17 has risen to the desired pressure, say, 1000 pounds per square inch. When that pressure has been attained, oil is supplied through the tubes 114 and 112 to actuate the trip 124 to operate the valve member 107 to connect the supply tube 105 to the tube 103, whereupon pressure fluid is supplied to the lower end of the valve B, as represented in the diagram Fig. 10, thereby causing the valve member of the valve B to move to the position opposite to that shown in the diagram, thus connecting the pressure supply pipe 79 to the pipe 73, at the same time blanking the pipe 66 and connecting the pipe 74 to the outlet port 76. Pressure fluid contained in the accumulator tank 78 under the predetermined pressure, say, 1000 pounds, then flows through the pipes 79 and 73 to the upper end of the cylinder 39, whereupon the plunger 37 is actuated to drive molten metal from the cylinder 33 into the impressions of the die and hold the metal under pressure while it is congealing.

The valve 100 allows pressure fluid to flow from the pipe 73 to the tube 99 when the pressure in the pipe 73 has risen to 1000 pounds. Pressure fluid flows to the upper end of the actuator 126^a for the trip 126 after a delay determined by the valve 128^a and thus causes said trip to restore the 40 valve member 107 to the normal or initial position shown in Figs. 10 and 12. In such restoration of the valve member 107, the arm 125 restores the trip member 124 and the sleeve valve 121 to their initial positions, as shown in Fig. 10. 45 The restoration of the valve member 107 causes the pressure supply tube 105 to be connected to the tube 104, whereby the valve member of the valve B is returned to the position shown in Fig. 10, and pressure is supplied through the pipes 66 and 74 to retract the plunger 37 in the pump cylinder 33, the pipe 73 being connected to the exhaust port 75 and the drain pipe 67. The valves 100 and 128^a insure the lapse of sufficient time between the metal-injecting and plunger-withdrawing movements so that the metal in the die shall have time to harden.

After the pressure in the pipe 74 has reached 1000 pounds, the valve 102 allows oil to flow through the tube 101 to the valve 102^a, and thence to the upper end of the actuating cylinder 95 for the trip 97, thus causing resetting of the valve member 91 to the position shown in Figs. 10 and 11. Such resetting of the valve member 91 connects the supply tube 90 with the tube 87, whereby the valve member of the valve A is returned to the position shown in Fig. 10. The supply pipe 66 is thereby connected to the pipe 69, thus causing the piston 19 to be lifted, and unlocking and opening the die. The length of time that shall elapse after the pump plunger 37 has been retracted and before the unlocking and opening of the die is determined by the valves 102 and 102^a.

Pressure flows from the pipe 69 through the 75

tube 111 to the actuator 126^a to reset the trip 126.

The apparatus herein disclosed is adapted to perform the operations involved in closing the die-sections, injecting the metal and reopening the die-sections in a few seconds.

The operator now operates the lever 130 to supply pressure fluid to the cylinder 46, thus causing the castings to be disengaged from the die-section 12. The release of the lever 130 completes a cycle of operations.

As soon as the accumulator 78 acted to drive oil under high pressure into the upper end of the cylinder 39, the continuously-operating power unit 60 began recharging the accumulator with oil, oil under high pressure being thus available for another cycle of operations by the time the operator has wiped off the contacting faces of the die-sections, preliminary to operating the lever 94.

It will be seen that in the machine herein disclosed the closing and locking of the die, the insertion of the cores, the injection of the molten metal, the withdrawal of the cores, and the un-locking and opening of the die are effected automatically, rapidly, in correct sequence and at proper time intervals, thus reducing the attention and exertions of the operator to the minimum. The time intervals are variable through setting of the valves 102^a, 115^a and 128^a. Automaticity of operation is highly desirable, as the great pressure under which the molten metal is cast creates such hazards to persons in the vicinity of the machine that proper operation is essential.

While a pair of die-sections is being installed in the machine, and the necessary adjustments made to effect proper locking of the die, the supply of oil to the valve 113 may be cut off by closing the valve 115^a, thereby shutting off the hydraulic circuits that control all the apparatus except the cylinder 17, and thus permitting the cylinder 17 to be operated without danger that molten metal shall be supplied to the die.

While I have described the construction herein shown with considerable particularity, it should be understood that the invention is not limited to the details illustrated, and that various changes may be made without departing from the scope of the invention as defined in the appended claims.

For the sake of brevity, the hydraulic cylinders and pistons for operating the die, the molten-metal pump and the ejector will be referred to in the claims as rams.

I claim as my invention:

1. In an automatic die-casting machine having a die adapted to be opened and closed, and a reciprocating-piston pump for forcing molten metal into the die, a hydraulic ram connected to open and close the die, a second hydraulic ram connected to actuate the pump, a source of hydraulic pressure connected to the rams, valve means in the connections to the die ram, valve means in the connections to the pump ram, a valve controlling the operation of the first valve means, a second valve controlling the operation of the second valve means, the first valve being arranged to be manually operated in one direction, means automatically actuated in the closing of the die for operating the second valve to operate the second valve means to actuate the pump to force metal into the die, means for thereafter automatically actuating the second valve to operate the second valve means to restore the second ram, and means for thereafter automatically operating the first valve to operate the first valve means to cause the die ram to open the die.
2. In an automatic die-casting machine having a die adapted to be opened and closed, and means for forcing molten metal into the die, a hydraulic ram connected to open and close the die, a second hydraulic ram connected to actuate the metal forcing means, fluid-pressure means for automatically actuating the first ram to close the die, then actuating the second ram to cause the metal-forcing means to force metal into the die, then actuating the second ram to restore the metal-forcing means to idle position, and then actuating the first ram to open the die, and manually operable means to initiate operation of said fluid-pressure means.
3. In an automatic die-casting machine having a die adapted to be opened and closed, and a reciprocating-piston pump for forcing molten metal into the die, a hydraulic ram connected to open and close the die, a second hydraulic ram connected to actuate the pump, fluid-pressure means operated by the closing of the die to actuate the second ram to actuate the pump to force metal into the die, fluid-pressure means operated by such actuation of the second ram to actuate the pump in the opposite direction, fluid-pressure means operated by the last-mentioned actuation of the pump to actuate the first ram to open the die.
4. In an automatic die-casting machine having a die adapted to be opened and closed, and a reciprocating-piston pump for forcing molten metal into the die, a hydraulic cylinder and piston connected to open and close the die, a hydraulic cylinder and piston connected to actuate the pump, a source of hydraulic pressure, valve means controlling the supply of pressure to the die cylinder, valve means controlling the supply of pressure to the pump cylinder, a valve controlling the operation of the first valve means, a second valve controlling the operation of the second valve means, the first valve being arranged to be manually operated in one direction.
5. A die-casting machine having, in combination, a platen, a die-section detachably secured to the platen, guide members secured to the platen perpendicularly thereto, a carriage mounted on said guide members to move toward and away from the platen, a coacting die-section detachably secured to the carriage, a frame adjustably mounted on said guide members, means including a pair of toggle links connecting the carriage to the frame, a second pair of toggle links connecting the midpoint of the first pair to said frame, and a hydraulic cylinder pivotally mounted on said frame and having a piston connected to the midpoint of the second pair of toggle links, for reciprocating the carriage and locking it in closed-die position.
6. A die-casting machine having, in combination, a platen, a die-section secured thereto, a coacting die-section, and means for moving the latter section and for locking it in contact with the other die-section, said means including a toggle connecting the second-mentioned die-section to a stationary point, a second toggle connected at one end to the mid-point of the first toggle and at its other end to a stationary point located at one side of the path of movement of the second-mentioned die-section, and a hydraulic ram connected to the mid-point of the second toggle and located at one side of the path of travel of the second-mentioned die-section.

7. In an automatic die-casting machine, in combination, a die, a reciprocatory pump for forcing molten metal into the die, a hydraulic ram for closing and opening the die, a second hydraulic ram for causing said pump to force metal into the die and for then returning the pump to its initial position, fluid-pressure means operated by the closing of the die to actuate the second ram to cause the pump to force metal into the die and then return the pump to its initial position, and fluid-pressure means operated upon the return of the pump to its initial position to actuate the first ram to open the die.
8. In an automatic die-casting machine, in combination, a die, a reciprocatory pump for forcing molten metal into the die, a hydraulic

ram for closing and opening the die, a second hydraulic ram for operating said pump through a cycle comprising forcing metal into the die and then returning to its initial position, fluid-pressure means for actuating the first ram to close the die, fluid-pressure means automatically operated by the closing of the die to actuate the second ram to operate the pump through its cycle, said first-mentioned fluid-pressure means being automatically operated by the return of the pump to its initial position to actuate the first ram to open the die, and manually operable means to initiate operation of the first-mentioned fluid-pressure means.

FRANK LANNERT. 15
